Lumber Company, Inc., Topeka, Kans., a corporation
of Kansas

Application February 24, 1958, Serial No. 49,763

Term of patent 14 years

(Cl. D16—2)

Fig. 3.

Fig. 1 is a perspective view of the front and top of a laboratory desk unit with the drawers and access doors of the cabinets closed, showing my new design;

Fig. 2 is a perspective view of the front, top, and right side thereof on a reduced scale, with the access doors open and the rack, bin and drawer of the cabinets in a pulled out position;

Fig. 3 is a left side elevational view of Fig. 2 on a further reduced scale, with a portion of the faucet being broken away for convenience of illustration; and

Fig. 4 is a rear elevational view of Fig. 3.

I claim:

The ornamental design for a laboratory desk unit, as shown.
